INVENTOR
Wilhelm Falkenberg
BY George E. Hinrichs
ATTORNEY.

UNITED STATES PATENT OFFICE.

WILHELM FALKENBERG, OF NEW YORK, N. Y., ASSIGNOR TO ALBERT WIELICH, OF NEW YORK, N. Y.

ELECTRICITY-APPORTIONING APPARATUS.

Application filed June 6, 1923. Serial No. 643,746.

To all whom it may concern:

Be it known that I, WILHELM FALKENBERG, a citizen of Germany, residing at New York, county of New York, and State of New York, have invented certain new and useful Improvements in Electricity-Appportioning Apparatus, of which the following is a specification.

The present invention relates to an electricity apportioning apparatus or dosimeter, and it is the principal object of the invention to provide an instrument of this character for use by physicians which allows a precise apportioning of the electric impulses during the treatment of a patient as for instance with cathode rays.

The regulation of the rays in the known instruments of this kind is effected by means of a set screw which acting upon the interruptor, allows a regulation of the treatment of rays. A regulation by a set screw naturally is uncertain and does not permit a physician to keep up a treatment by such rays in certain prescribed doses as he has no means at his disposal to control the exact doses used.

It is the object of the present invention to overcome these disadvantages by providing means visibly indicating the exact number of impulses or doses of electricity supplied to a patient during his treatment with ultraviolet and other rays, as an overdose of such rays will eventually result in serious injuries.

Another object of the invention is the combination of a regulating set screw for the interruptor with an indicating device allowing the setting of the apparatus for any desired apportionment of the electric impulses.

Other objects and advantages of my invention will become more fully known as the description thereof proceeds, and will then be more specifically pointed out in the appended claims.

In the accompanying drawing forming a material part of this disclosure:

Figure 1 is a section through the bottom plate of a high frequency apparatus in which the apportion indicator apparatus is mounted.

Figure 2 is a top plan view of the indicator mechanism.

In the drawing 10 designates the bottom

plate of a high frequency apparatus in 55 which the indicator for the apportioning device is mounted. A set screw 11 is engaging the bottom plate 10, and its end is engaging the interrupter (wagnerian hammer) to bring the same into more or less 60 close contact with the magnet in order to produce a change in the oscillations.

These elements are well known and do not form a part of the present invention.

The set screw 11 carries a toothed wheel 65 or gear 12, which is in mesh with a gear 13 loosely mounted to rotate around a pin 14.

The gear 13 engages another gear 15 loosely rotating around a pin 16 secured to bottom plate 10 in approximately the central axis thereof. A cover plate 18 covers the gear wheels and the bottom plate 10. The hub 19 of gear 15 extends through plate 18 and carries at its outer end a hand 20.

Between plate 18 and gear 15, a plate 21 75 is provided which has a bushing 22 made integrally therewith which is adapted to rotate around the hub 19 of gear 15. This bushing extends through the plate 18, and carries a large hand 23. The plate 21 is preferably made of elastic material so that it frictionally engages the gear 15 in a depression of the same and is taken along when the gear 15 is rotated by the rotation of set screw 11. The cover plate 18 carries two 85 dials 24 and 25, and when in the position marked 26, both hands 20 and 23 are aligned and cover each other. In this position the gear 15 and plate 21 are coupled, and if now the set screw 11 is rotated, both hands 90 will be displaced and travel together from position 26 to a position marked 27. If the rotation of the hands is continued, the large hand 23 will engage a pin 28, while the small hand will continue its motion as now 95 and plate 21 is interrupted.

The small hand then indicates the large apportionment from 12 to 23 and in this manner it is possible to indicate the comparatively insignificant axial displacement of the set screw visibly by means of the clearly visible position of the hands, which allows the physician to clearly and minutely ascertain the exact doses of electricity which he intends to use for the specific treatment.

It will be clear that changes may be made in the general arrangement and in the con-

struction of the minor details of my invention without deviating from the scope and spirit thereof as it is defined in the claims.

Having thus described my invention, 5 what I claim as new and desire to protect by Letters Patent is:

1. In a dosimeter, including a casing having a plurality of dial indications, a long indicator adapted for cooperation with one set 10 of indications, a shorter indicator for cooperation with the other set of indications, and means for operating the indicators, said means comprising mechanism to permit the indicators to move as a unit to a predetermined point and thereafter permit one of 15 the indicators to continue the movement in the same direction independently of the other indicator.
2. In a dosimeter, a casing having a plurality of concentrically arranged dial indications, a plurality of indicators of different lengths for cooperation with the respective sets of indications, means for limiting the movement of one of the indicators in one 20 direction, and means operating on a com-

mon axis for movement of both indicators as a unit to the point of limit of movement of one indicator and thereafter move the other indicator in the same direction independent of the limited indicator.

3. A dosimeter, comprising a casing, having a plurality of concentric dial indicators, an axial pin for the casing, a gear rotatable on the pin and having a hub portion extending lengthwise the pin, a pointer carried by said hub portion, a friction member encircling the hub portion, a pointer carried by the friction member and of greater length than the first mentioned pointer, means carried by the casing beyond the range of movement of the first mentioned pointer to limit the movement of the second mentioned pointer, and means to operate said gear at will, the respective pointers co-operating with the respective dial indications.

In testimony whereof I have affixed my signature.

WILHELM FALKENBERG.
